UNITED STATES PATENT OFFICE.

JOHN W. KILLINGSWORTH, OF ATLANTA, GEORGIA.

SPRING-CAMMING MACHINE.

Application filed March 21, 1927. Serial No. 177,179.

This invention relates to a spring camming machine and has for its object to provide, in a manner as hereinafter set forth, a machine of such class for efficiently camming springs 5 of the laminated type, but it is to be understood that a machine in accordance with this invention, can be employed for any purposes for which it is found applicable.

A further object of the invention is to provide, in a manner as hereinafter set forth, a machine for the purpose set forth including a pair of opposed coacting camming elements, one operated by fluid pressure and the other highly tensioned, indestructible and 15 flexible and with the tension therefor created by a pair of spaced semi-elliptical springs co-acting, when the camming operation is carried out for the camming of the springs in an expeditious and a thoroughly efficient 20 manner.

Further objects of the invention are to provide, in a manner as hereinafter set forth, a spring camming machine which is comparatively simple in its construction and arrangement, strong, durable, compact, adjustable, 25 thoroughly efficient in its use, readily assembled, and comparatively inexpensive to set up.

With the foregoing and other objects in view the invention consists of the novel construction, combination and arrangement of parts, as hereinafter more specifically described and illustrated in the accompanying drawings, wherein is shown an embodiment 35 of the invention, but it is to be understood that changes, variations and modifications can be resorted to which fall within the scope of the claims hereunto appended.

In the drawings wherein like reference 40 characters denote corresponding parts throughout the several views:

Figure 1 is a top plan view of a spring camming machine in accordance with this invention.

Figure 2 is a front elevation thereof.

Figure 3 is an end view.

Figure 4 is a fragmentary view in cross section.

Figure 5 is a top plan view, upon a reduced 50 scale, of the table or platform.

Figure 6 is a perspective view of one of the adjustable abutments.

Referring to the drawings in detail 1 denotes a rectangular table top or platform provided with a depending edge flange 2 which is coextensive therewith. The top 1 in prox-

imity to its forward side edge and each end edge is formed with an opening and said openings are indicated at 3, 4. The top 1 in proximity to its rear edge and at each side 60 of its transverse median is provided with an opening and said openings are indicated at 5, 6. The top 1 adjacent its rear edge and in proximity to each end edge is formed with a group of openings and the said groups are indicated at 7, 8. Arranged at the longitudinal center of the top 1 is a pair of spaced lengthwise extending slots 9, 10. Each slot extends from a point at one side of the transverse median of the top and terminates at a 70 point adjacent an end edge of the top. Formed integral with the lower face of the top 1, at the transverse median thereof is a web 11 of rectangular cross section and which extends from the rear to the front flange 2. 75 The web 11 at the front of the table 1 merges into a supporting arm 12 which projects forwardly of the front of the top 1 a substantial distance and is of rectangular cross section. The arm 12 is formed near each side edge 80 with a set of spaced openings 13. The arm 12 is positioned below the flange 2 at the front of the table top 1. The openings 5, 6 extend through the web 11. Secured against the lower face of the top 1 in proximity to the 85 end flanges 2 are supporting standards 14 of skeleton form, and each is provided at its bottom with a pair of flanges 15 through which extend holdfast devices 16 for fixedly securing the standards stationary. Each 90 standard consists of an inverted yoke shaped portion 17 provided with a brace 18 which is integral with the top of the body portion 17 and also with the arms thereof. The means for securing the standards 14 to the top 1 will 95 be presently referred to.

Positioned upon the upper face of the top 1 in proximity to the ends thereof, are end brackets 19 of inverted U-shape and each of which is formed at its lower end with a pair 100 of lateral flanges 20, through which extend holdfast devices 21 for fixedly securing the brackets in position. The holdfast devices 21 at the rear of the bracket 20, extend through one of the openings of each group 7 105 and 8 and also through the top of the body portion 17 of the standards 14. The holdfast devices 21 at the outer end of the brackets 19 extend through the openings 3 and 4 and also through the body portion 17 of the 110 standard 14. Mounted upon the upper ends of the brackets 19, centrally thereof, and dis-

posed longitudinally with respect to the top 1, is a stop 22 in the form of an inverted channel bar and which has its ends fixedly secured to the brackets 19 by the holdfast devices 23. 5 Positioned against the lower face of the top 1 of each of the brackets 19, below the stop 22, is a hanger member 24, having its lower part provided with a rearward extension 25, formed with an opening 26. Supported by 10 the extension 25 is a cylindrical supporting member 27 in the form of a pipe and which is disposed longitudinally with respect to the table top as well as being arranged a substantial distance thereabove. 15 Adjustably mounted on the support 27 is a pair of abutment blocks 28, which are vertically disposed, are slidably mounted in the slots 9, 10 extend above the brackets 19 and bear against the front side of the stop 22. Each block 28 is 20 provided with a rearward extension 29, formed with an opening 30 through which extends the support 27. The blocks 28 or rather abutments 28 are adjustable relatively to each other upon the support 27. The ends 25 of the slots 9, 10 limit the adjusting movement of the abutments 28 in either direction.

Arranged on the top 1, in proximity to each of the brackets 19, is a tensioning element for the flexible camming element. Each 30 tensioning element is in the form of a half elliptic spring. The tensioning elements are indicated at 31, 32, and have their rear or larger ends connected to yokes 33, which are fixedly secured by the holdfast devices 34 to the table top. One of the holdfast devices 35 extends through one of the openings of the group 7 and the other holdfast device 34 through one of the openings of the group 8. Associated with each tensioning element is 40 a set screw 35, carried by a bracket 36, which is fixedly secured to the table top by holdfast devices and the holdfast devices for the brackets extend through another opening of the groups 7 and 8. The set screws 35 are oppositely disposed with respect to each other and this arrangement also applies to the tensioning elements 31, 32. The tensioning elements project forwardly with respect to the stop 22 and abutments 28.

50 The flexible camming element is arranged longitudinally with respect to the table top 1 and forward of the slots 9, 10. The flexible camming element has its ends connected to the forward ends of the tensioning elements 31 and 32 and said flexible camming element is referred to generally by the reference character 37. The element 37 is formed of a series of interengaging, upstanding, intermediate, oppositely disposed units 38 constructed of steel and each having one face provided with a lengthwise extending dovetailed groove 39. The said element 37 further includes a pair of upstanding end members 40, 41, constructed from a steel plate and each 60 having the outer end thereof formed with a

pair of spaced barrels 42, 43 and its inner end with an L-shaped flange 44 engaging in an outer unit of the intermediate units of the element 37. The outer ends of the tensioning elements 31, 32 are provided with barrels 45 70 arranged between the barrels 42, 43. The barrels of the tensioning elements 31, 32 align with the barrels of the end unit or members 40, 41 of the camming element 37. The alining barrels are connected together by a pivot 75 bolt 46 carrying a securing nut 47. The end portion or end units 40, 41 are of greater width than the width of the units of the intermediate portion of the element 37. The normal position of the camming element 37 is as 80 shown in Figure 1.

Opposing, arranged forwardly of and spaced from the camming element 37, is a fluid pressure operated camming element or shoe 48 of segmental contour and which forms 85 the head of a plunger 49 operated by a fluid pressure actuated shifting device 50 therefor. The plunger 49 extends into the device 50 and is operated by the piston thereof, the latter not being shown. A fluid pressure supply 90 pipe 51 is provided for the device 50 and said pipe 51 carries a cut-off 52. The device 51 is mounted on the supporting arm 12 and is fixedly secured therewith by the holdfast devices 53. The device 50 carries a rearwardly 95 extending guiding means 54 for the plunger 49.

100 Mounted upon the top 1, at the transverse center thereof is a vertically disposed block 55, provided with an opening 56 formed with threaded walls. The opening 56 is arranged transversely with respect to the table top 1. The block 55 at its bottom is formed with oppositely extending flanges 57, through which extend holdfast devices 58 for fixedly securing the block to the table top. The holdfast devices extend through the openings 5 and 6 and also through the web 11. Threadably engaging with the wall of the opening 56 is an adjusting rod 59 provided at its outer end 110 with a hand wheel 60 for the purpose of revolving it. The inner end of the rod 59 carries an abutment 61, which is disposed at the transverse median of the table top and is arranged in alinement with the camming element or shoe 48, but is spaced rearwardly with respect thereto and also rearwardly with respect to the element 37, but is disposed centrally with respect to the latter. The abutment 61 provides means for limiting the inward movement of the central part of the intermediate portion of the camming element 37. When the camming element 37 is shifted rearwardly, it bends on the abutments 28. The position of the spring to be cammed relative to the elements 37 and 48 is shown in dotted lines and indicated at 62, Figure 1.

115 The semi-elliptic springs 31, 32, which form the tensioning elements for the camming element 37, provide for a high degree of tension 120 125 130

for the camming element 37, whereby when the elements 37 coact with the element 48, a thoroughly satisfactory camming of the spring is had due to the fact that the spring 5 cannot move quickly rearwardly during the bending action owing to the fact that the element 37 is highly tensioned. The manner of setting up the intermediate units 38 in connection with the outer units 40, 41 form substantially what may be termed an indestructible camming element 37. The screws 35 provide for the setting of the elements 31, 32 the desired manner and the adjustability of the abutments 28 enable the operator to set the 15 bow in the spring the desired length, and further the abutment 61 will provide for the desired depth of bow or cam with respect to the spring.

It is thought the many advantages of a 20 spring camming machine in accordance with this invention can be readily understood, and although the preferred embodiment of the invention is as illustrated and described, yet it is to be understood that changes in the 25 details of construction can be had which will fall within the scope of the invention as claimed.

What I claim is:

1. In a spring camming machine a flexible camming element consisting of an intermediate portion and a pair of end portions, said intermediate portion formed of a series of upstanding units each provided on one face with a dove-tail groove, said units being oppositely disposed and interengaging with each other, and each of said end portions having one end provided with means interengaging with an outer unit of the intermediate portion and its other end provided with means for connection with a tensioning element therefor. 30
2. In a spring camming machine a flexible camming element, a pair of oppositely disposed horizontally extending semi-elliptical springs providing tensioning elements for the camming element and each having its inner end anchored and its outer end pivotally connected directly to one end of the camming element, and setting means for and at the inner side of each of said tensioning elements. 45
3. In a spring camming machine a fluid pressure operated camming shoe, a flexible camming element arranged rearwardly of and coacting with said shoe to cam the spring, and a pair of horizontally disposed spaced semi-elliptic springs, each having its outer end pivotally connected to one end of the camming element, and a stationary anchoring means for each spring, each of said springs having its rear end fixedly secured to an anchoring means. 55
4. In a spring camming machine a fluid pressure operated camming shoe, a flexible camming element arranged rearwardly of and coacting with said shoe to cam the spring, and further of greater length than the length 60
5. In a spring camming machine a fluid pressure operated camming shoe, a flexible camming element arranged rearwardly of and coacting with said shoe to cam the spring, and further of greater length than the length 65
6. A camming machine comprising a table formed with a pair of slots, a fluid pressure operated camming shoe supported from and over said table, a flexible camming element positioned over the table, arranged rearwardly of and coacting with said shoe to cam the spring, a pair of spaced semi-elliptic springs arranged over the table and each having its outer end connected with one end of the camming element and its rear end anchored to the table, a pair of slidably adjustable abutments extending into said slots and arranged rearwardly of and for said camming element, 70
7. A camming machine comprising a table formed with a pair of slots, a fluid pressure operated camming shoe supported from and over said table, a flexible camming element of belt like form positioned over the table, arranged rearwardly of and coacting with said shoe to cam the spring, a pair of spaced semi-elliptic springs arranged over the table and each having its outer end connected with one end of the camming element and its rear end anchored to the table, a pair of slidably adjustable abutments extending into said slots and arranged rearwardly of and for said camming element, 75
8. A camming machine comprising a table formed with a pair of slots, a fluid pressure operated camming shoe supported from and over said table, a flexible camming element arranged rearwardly of the slidable abutments and disposed centrally with respect to and rearwardly of the camming element, supporting means for said slidable abutments, and a stop for and positioned rearwardly of said slidable abutments. 80
9. A camming machine comprising a table formed with a pair of slots, a fluid pressure operated camming shoe supported from and over said table, a flexible camming element arranged rearwardly of the slidable abutments and disposed centrally with respect to and rearwardly of the camming element, supporting means for said slidable abutments, and a stop for and positioned rearwardly of said slidable abutments. 85
10. A camming machine comprising a table formed with a pair of slots, a fluid pressure operated camming shoe supported from and over said table, a flexible camming element positioned over the table, arranged rearwardly of and coacting with said shoe to cam the spring, a pair of spaced semi-elliptic springs arranged over the table and each having its outer end connected with one end of the camming element and its rear end anchored to the table, a pair of slidably adjustable abutments extending into said slots and arranged rearwardly of and for said camming element, 90
11. A camming machine comprising a table formed with a pair of slots, a fluid pressure operated camming shoe supported from and over said table, a flexible camming element of belt like form positioned over the table, arranged rearwardly of and coacting with said shoe to cam the spring, a pair of spaced semi-elliptic springs arranged over the table and each having its outer end connected with one end of the camming element and its rear end anchored to the table, a pair of slidably adjustable abutments extending into said slots and arranged rearwardly of and for said camming element, 95
12. A camming machine comprising a table formed with a pair of slots, a fluid pressure operated camming shoe supported from and over said table, a flexible camming element arranged rearwardly of and coacting with said shoe to cam the spring, a pair of spaced semi-elliptic springs arranged over the table and each having its outer end connected with one end of the camming element and its rear end anchored to the table, a pair of slidably adjustable abutments extending into said slots and arranged rearwardly of and for said camming element, 100
13. A camming machine comprising a table formed with a pair of slots, a fluid pressure operated camming shoe supported from and over said table, a flexible camming element of belt like form positioned over the table, arranged rearwardly of and coacting with said shoe to cam the spring, a pair of spaced semi-elliptic springs arranged over the table and each having its outer end connected with one end of the camming element and its rear end anchored to the table, a pair of slidably adjustable abutments extending into said slots and arranged rearwardly of and for said camming element, 105
14. A camming machine comprising a table formed with a pair of slots, a fluid pressure operated camming shoe supported from and over said table, a flexible camming element arranged rearwardly of and coacting with said shoe to cam the spring, a pair of spaced semi-elliptic springs arranged over the table and each having its outer end connected with one end of the camming element and its rear end anchored to the table, a pair of slidably adjustable abutments extending into said slots and arranged rearwardly of and for said camming element, 110
15. A camming machine comprising a table formed with a pair of slots, a fluid pressure operated camming shoe supported from and over said table, a flexible camming element of belt like form positioned over the table, arranged rearwardly of and coacting with said shoe to cam the spring, a pair of spaced semi-elliptic springs arranged over the table and each having its outer end connected with one end of the camming element and its rear end anchored to the table, a pair of slidably adjustable abutments extending into said slots and arranged rearwardly of and for said camming element, 115
16. A camming machine comprising a table formed with a pair of slots, a fluid pressure operated camming shoe supported from and over said table, a flexible camming element arranged rearwardly of and coacting with said shoe to cam the spring, a pair of spaced semi-elliptic springs arranged over the table and each having its outer end connected with one end of the camming element and its rear end anchored to the table, a pair of slidably adjustable abutments extending into said slots and arranged rearwardly of and for said camming element, 120
17. A camming machine comprising a table formed with a pair of slots, a fluid pressure operated camming shoe supported from and over said table, a flexible camming element of belt like form positioned over the table, arranged rearwardly of and coacting with said shoe to cam the spring, a pair of spaced semi-elliptic springs arranged over the table and each having its outer end connected with one end of the camming element and its rear end anchored to the table, a pair of slidably adjustable abutments extending into said slots and arranged rearwardly of and for said camming element, 125
18. A camming machine comprising a table formed with a pair of slots, a fluid pressure operated camming shoe supported from and over said table, a flexible camming element arranged rearwardly of and coacting with said shoe to cam the spring, a pair of spaced semi-elliptic springs arranged over the table and each having its outer end connected with one end of the camming element and its rear end anchored to the table, a pair of slidably adjustable abutments extending into said slots and arranged rearwardly of and for said camming element, 130

abutments and further arranged rearwardly of and centrally with respect to said camming element, and setting means for said semi-elliptic springs arranged rearwardly of 5 said adjustable abutments.

8. In a spring camming machine a flexible camming element, a platform arranged therebelow, a pair of oppositely disposed horizontally extending semi-elliptical springs 10 standing on a longitudinal edge thereof and providing tension elements for the camming element, each of said springs having its inner end free of movement and anchored to said platform and its outer end extending into 15 one end of the camming element, and pivot bolts between the ends of the camming element and the outer ends of said springs.

9. In a spring camming machine a flexible camming element, a platform arranged 20 therebelow, a pair of oppositely disposed horizontally extending semi-elliptical springs standing on a longitudinal edge thereof and providing tension elements for the camming element, each of said springs having its inner 25 end anchored to said platform and its outer end extending into one end of the camming element, pivot bolts between the ends of the camming element and the outer ends of said springs, and setting means for said 30 tensioning elements, said means positioned at the inner side and forwardly of the inner ends of said elements.

10. In a spring camming machine a flexible camming element, a pair of horizontally 35 disposed semi-elliptic springs providing tensioning elements for the camming element, and each of said tensioning elements having the inner end thereof anchored and its outer end extending into one end of the camming 40 element, and pivot bolts between the ends of the camming element and the outer ends of said springs.

11. In a spring camming machine a flexible camming element, a pair of horizontally 45 disposed semi-elliptic springs providing tensioning elements for the camming element, each of said tensioning elements having the inner end thereof anchored and its outer end pivotally connected to one end of the camming 50 element, and each of said springs standing on a longitudinal edge thereof throughout.

12. In a spring camming machine a flexible camming element, a pair of horizontally 55 disposed semi-elliptic springs providing tensioning elements for the camming element, and each of said tensioning elements having the inner end thereof anchored and its outer end extending into and pivotally connected to 60 one end of the camming element, and setting

means for said springs positioned forwardly of the anchored ends thereof.

13. In a spring camming machine, a flexible camming element consisting of an intermediate portion and a pair of end portions, 65 said intermediate portion formed of a series of vertically disposed units each provided on one face with a dove-tailed groove, said units oppositely disposed and interengaging with each other, and each of said end portions having the inner part thereof provided with means for interengaging with an outer unit of the intermediate portion and its outer portion extended and provided with means for pivotal connection with a tensioning element therefor.

14. In a spring camming machine, a flexible camming element, a platform arranged therebelow, a pair of oppositely disposed, horizontally extending tensioning elements 80 arranged over the platform, stationary anchoring means for the inner ends of said tensioning elements, the ends of said camming and the outer ends of the tensioning elements interengaging with each other, and means 85 extending through said interengaging ends for pivotally connecting the camming element to the tensioning elements.

15. In a spring camming machine, a flexible camming element, a platform arranged 90 therebelow, a pair of oppositely disposed, horizontally extending tensioning elements arranged over the platform, stationary anchoring means for the inner ends of said 95 tensioning elements, the ends of said camming and the outer ends of the tensioning elements interengaging with each other, means extending through said interengaging ends for pivotally connecting the camming element to the tensioning elements, and said 100 platform provided with means to permit of selectively positioning said anchoring means.

16. In a spring camming machine, a flexible camming element, a platform arranged therebelow, a pair of oppositely disposed, 105 horizontally extending tensioning elements arranged over the platform, stationary anchoring means for the inner ends of said tensioning elements, the ends of said camming and the outer ends of the tensioning elements 110 interengaging with each other, means extending through said interengaging ends for pivotally connecting the camming element to the tensioning elements, and means anchored on the platform and positioned in proximity 115 to the inner sides of said tensioning elements for setting these latter.

In testimony whereof, I affix my signature hereto.

JOHN W. KILLINGSWORTH.
